CLAIM

The ornamental design for a hearing aid for the deaf, as shown and described.

DESCRIPTION

1. Hearing aid for the deaf

Figure 1.1 is a perspective view of a hearing aid for the deaf; Figure 1.2 is a right view thereof; Figure 1.3 is a left view thereof; Figure 1.4 is a front view thereof; Figure 1.5 is a back view thereof; Figure 1.6 is a top view thereof; and, Figure 1.7 is a bottom view thereof.

The broken lines shown in Figures 1.1-1.7 illustrate portions of the hearing aid for the deaf which form no part of the claimed design.
